BAND-SPREAD TUNING MECHANISM

Frederik Hendrik Gusdorf, Eindhoven, Netherlands, assignor to Radio Corporation of America, New York, N. Y.

Application May 11, 1940, Serial No. 334,499
In Germany June 22, 1939

4 Claims. (Cl. 74—10)

In the copending application of Arnold T. Vossen, Ser. No. 297,972, filed October 5, 1939, there is described a device for obtaining band-spreading in short-wave reception. In one of the examples described therein the band-spread tuning means are constituted by inductance coils included in the oscillatory circuits to be tuned and in the field of which members seated on a shaft can be displaced by means of a screw thread driving the shaft.

The present invention relates to a radio receiver as described in the above application in which band-spread tuning means are displaced by a transmitting mechanism which also displaces the pointer of the band-spread scale.

The invention has for its object to enable preliminary adjustment of the band-spread means in two positions.

In the manufacture of a number of identical band-spread tuning means it is impossible from the economical point of view to equalize them completely.

It is well known to make the band-spread tuning means variable so that the band-spread scale is correct at at least one point.

According to the invention the starting point and the length of the path which the band-spread tuning means traverse during a complete displacement of the pointer can be adjusted independently of each other.

When the band-spread tuning means are constituted by elements mounted on a shaft and displaced in the field of inductance coils associated with the oscillatory circuits to be tuned the shaft can be adjusted in the direction of its length according to a suitable embodiment of the invention.

In this case the shaft is preferably driven by the intermediary of a lever with which the ratio between the distances of the point of power and the point of load from the point of rotation can be varied.

In this case the movement of the lever can be transmitted to the shaft by the intermediary of a member provided with a set screw which is in line with the shaft and bears on this shaft and with a set screw which in one of the extreme positions of the member is parallel with the lever and which serves for the adjustment of the ratio between the distances of the point of power and the point of load from the point of rotation.

In order that the invention may be clearly understood and readily carried into effect it will now be described more fully with reference to the accompanying drawings, in which

Fig. 1 shows an oscillatory circuit including a band-spread tuning element.

Fig. 2 is a graph of the variation of the inductance of such an oscillatory circuit as a function of the displacement of the band-spread tuning element.

Fig. 3 shows part of the transmitting mechanism between the tuning knob serving for band-spreading and the band-spread tuning means to be driven.

Fig. 4 shows the entire transmitting mechanism.

The oscillatory circuit shown in Fig. 1 includes a fixed inductance L_1 in series with a variable inductance L_2 . A tuning condenser C_1 and a trimmer condenser C_2 are connected in parallel therewith.

The tuning circuit can be tuned in the entire short short-wave range (for example from 13 meters to 50 meters) by means of the tuning condenser C_1 . By means of the inductance L_2 band-spread tuning can be effected within a number of comparatively narrow short-wave bands. For this purpose tuning is first effected by means of the condenser C_1 to the center of the desired band, after which tuning within the band concerned is effected by means of the variable inductance L_2 . The variation in inductance of the inductance coil L_2 is several per cent of the inductance of the inductance coil L_1 . The trimmer condenser C_2 permits of correcting the tuning of the oscillatory circuit at a low value of the tuning condenser C_1 , for example 18 meters, and of altering the main tuning scale to accord at one point. This must be effected at a low value of C_1 since in this case the relative variation of C_2 is the greatest. If, for example, the main tuning scale is correct at 18 meters the influence of C_2 at 43 meters is negligible. The main tuning scale can be made correct at a second point, for example at 43 meters, by adjusting the fixed inductance of the oscillatory circuit. Since the inductance at 18 meters is the same as the inductance at 43 meters a variation of the inductance at 43 meters exercises the same relative influence on the tuning at 18 meters. It is known to bring about this variation in inductance by means of a small variable inductance coil in series with the fixed inductance. The invention permits however, of corrections of inductance being made by means of the band-spread tuning means.

Fig. 2 shows a system of coordinates XOY , the inductance of the oscillatory circuit being plotted as an ordinate and the displacement of the band-spread tuning means being plotted as an abscissa.

The inductance of the coil L_1 is plotted as a negative ordinate. In series with the coil L_1 is connected the variable coil L_2 whose inductance can be altered between two limits L_3 and L_4 . The total inductance consequently varies from L_1+L_3 to L_1+L_4 . The variation in inductance L_4-L_3 serves for the band-spread tuning. The adjustment of the starting value L_3 permits of the main scale being rendered correct at a second point.

Referring to Fig. 2, *a* and *b* designate two characteristics of the inductance as a function of the displacement of two band-spread tuning elements which are not entirely identical.

Since the two band-spread tuning elements have to exhibit the same starting inductance L_3 and the same final inductance the starting displacement of the band-spread tuning element having the characteristic *a* is p_a , where as the tuning displacement is q_a . For the other band-spread tuning element these displacements are p_b and q_b . It is therefore necessary to arrange between the band-spread tuning knob and the band-spread tuning elements a transmitting mechanism by means of which the displacements p and q can previously be adjusted for each band-spread tuning element so that a complete displacement of the pointer of the band-spread scale results in a variation in inductance from L_1+L_3 to L_1+L_4 .

Fig. 3 shows that part of the transmitting mechanism by means of which the two displacements p and q can be adjusted.

The transmitting mechanism comprises a part *1* adapted to slide on a shaft *2* which serves as a straight guide. The part *1* has mounted on it a set screw *3* which is in line with the shaft (shown at *39* in Fig. 4) that carries the band-spread tuning means. This shaft, which is not shown in Fig. 3, engages the end surface *4* of the set screw *3*. The part *1* comprises in addition an angularly arranged set screw *5* which is provided at the end with a disc *6*. The disc *6* engages an upright edge *7* of a lever *8* adapted to rotate on a shaft *9*. The lever *8* is shown in Fig. 3 in full lines in one of its extreme positions and in dotted lines in the other extreme position *8'*. The lever *8* can be moved into any of the positions intermediate the said two extreme positions by means of the band-spread tuning knob and a screw not shown in detail in Fig. 3.

When the lever *8* is moved into the position *8'* the screw *5* is displaced towards the position *5'* shown in dotted lines because the part *1* is forced against the lever *8* by a spring (not shown) acting on the shaft of the band-spread tuning means.

On the screw *5* being screwed into the position *10* shown in dotted lines when the lever *8* occupies the position shown the part *1* is not displaced since the screw *5* is parallel with the lever *8*.

If, however, the lever *8* is moved into the position *8'* the screw *5* is displaced into the position *10'* and the part *1* traverses a correspondingly smaller path.

The starting point *p* and the path *q* of the band-spread tuning means can be adjusted by means of the two set screws *3* and *5* and consequently independently of each other.

Fig. 4 shows the entire transmitting mechanism. Corresponding parts in Figs. 3 and 4 are designated by the same reference numerals.

Intermediate two plates *21* and *22* which are spaced apart by means of bolts *23* is arranged a shaft *24* which is partly provided with screw thread *25*.

The shaft *24* carries a rope drum *26* having wound in it the rope *27* of a flexible cable *28* which rope is connected with the pointer (not shown) of the band-spread tuning scale.

The rope drum *26* is coupled via a slipping coupling *29* to a gear wheel *30* adapted to be driven by a gear wheel *31* mounted on the shaft *32* of the band-spread tuning knob (not shown). The slipping coupling protects the screw thread *25* from being damaged. On the shaft *24* being rotated a threaded strap *33* is displaced over the shaft and along a straight guide *34* and thus drives the lever *8*. The lever *8* is adapted to rotate on a shaft *9* and is secured to the plate *21* by a strap *35*. The lever comprises two parts *8* and *36* connected by a rod *37*. The movement of the strap *33* is transmitted to the lever *8* via the rod *37*.

The movement of the lever *8* is transmitted to the part *1* in the manner described with reference to Fig. 3.

The part *1* is displaced not only on the shaft *2* but also along a straight guide *38*.

The end surface *4* of the screw *3* is engaged by a shaft *39* which is adapted to slide in a sleeve *40* and which is centered and guided by a plate *41*. The shaft *39* is forced against the end surface *4* by a spring (not shown). The shaft *39* carries an iron core *42* which is displaced, upon the shaft *39* being displaced in the field of coil *43* wound around the sleeve *30* so that the inductance of this coil is varied. The coil *43*, (which corresponds to the coil *L₂* in Fig. 1) forms part of the oscillatory circuit to be tuned.

When it is desired to tune more than one oscillatory circuit a plurality of iron cores may be arranged on the shaft *39*. The place of the shaft *39* depends on the position of the end surface *4* of the screw *3*. The rotation of this screw *3* permits of adjusting the starting position of the shaft *39* and the final position of the shaft *39* can be adjusted by rotation of the screw *5* in the position shown of the lever *8*. The latter adjustment is effected at a maximum inductance of the coil *43*.

What I claim is:

1. In a radio receiver of the type provided with one or more permeability tuned circuits and wherein the tuning means for each such circuit is constituted by a magnetic core mounted on a shaft and displaceable in the field of an inductance coil included in the tuned circuit, means for actuating said shaft in the direction of its length, said means comprising a carrier movable in the direction of the shaft, settable means carried by said carrier for determining the initial adjustment of said shaft, additional settable means carried by said carrier for determining the extent of linear displacement of the shaft, means for actuating the carrier through said additional means, and manually operable means for controlling the movement of the carrier actuating means.

2. In a radio receiver of the type provided with one or more permeability tuned circuits, and wherein the tuning means for each such circuit is constituted by a magnetic core mounted on a shaft and displaceable in the field of an inductance coil included in the tuned circuit, means for actuating said shaft in the direction of its length, said means comprising a carrier movable in the direction of the shaft, adjustable screw means in alignment with the shaft carried by said carrier for determining the initial adjustment of said shaft and for actuating the same,

second adjustable screw means carried by said carrier for determining the extent of linear displacement of the shaft, means for actuating the carrier through the second adjustable screw means, and manually operable means for controlling the movement of the carrier actuating means.

3. In a radio receiver of the type provided with one or more permeability tuned circuits and wherein the tuning means for each such circuit is constituted by a magnetic core mounted on a shaft and displaceable in the field of an inductance coil included in the tuned circuit, means for actuating said shaft in the direction of its length, said means comprising a carrier movable in the direction of the shaft, a first settable means carried by said carrier and in alignment with the core shaft for determining the initial adjustment of said shaft and for actuating said shaft, a second settable means carried by said carrier for determining the extent of linear displacement of the shaft, a pivoted member for actuating the carrier through said second set-

table means, and manually operable means for controlling the movement of the pivoted member.

4. In a radio receiver of the type provided with one or more permeability tuned circuits and wherein the tuning means for each such circuit is constituted by a magnetic core mounted on a shaft and displaceable in the field of an inductance coil included in the tuned circuit, means for actuating said shaft in the direction of its length, said means comprising a carrier movable in the direction of the shaft, a first adjustable screw means in alignment with the shaft carried by said carrier for determining the initial adjustment of said shaft and for actuating the same, second adjustable screw means carried by said carrier for determining the extent of linear displacement of the shaft, a pivoted member for actuating the carrier through the second adjustable screw means, and manually operable means for controlling the movement of the pivoted member.

FREDERIK HENDRIK GUSDORF.
